DISTRIBUTION METHOD AND APPARATUS

Harold E. McCrery, Pittsburgh, Pa., assignor to
Blaw-Knox Company, Blawnox, Pa., a corpora-
tion of New Jersey

Application March 19, 1932, Serial No. 599,948

11 Claims. (Cl. 51—11)

My invention relates in general to the distribution of solids suspended in fluid streams and, in particular, to a method and means for obtaining a uniform distribution of abrading particles carried along in a blast of gas, usually air. Although the invention is described in detail herein-after with reference to its application to a method and apparatus of blasting, it is not limited to such application.

10 In the art of blasting as practiced heretofore and, particularly, the art of blasting metal sheets or plates for removing the scale therefrom, it is known to supply abrasive particles to an air stream, and to sub-divide the stream in order to 15 extend the abrasive effect thereof over a considerable area of the sheet or plate under treatment. Great difficulty has been encountered, however, in obtaining a uniform distribution of the abrasive material over the desired effective 20 area. As a result, some parts of the material being blasted are inadequately cleaned, while others are abraded to an unnecessary degree. This difficulty arises because the abrasive particles are not always uniformly distributed in the 25 air stream, particularly where the supply conduit is not substantially vertical, and the sub-divided passages are almost necessarily symmetrically disposed with respect to the supply conduit.

I have invented a method and apparatus for 30 distributing solid particles carried along in an air stream for the purpose of cleaning metal surfaces for galvanizing, welding or other treatments which insures a uniform distribution of the abrasive material and, therefore, a uniform effect 35 upon the metal being cleaned. In accordance with one form of the invention, I arrange the supply conduit as a vertical riser and take off the sub-divided passages from symmetrical points therein. These sub-divided passages may 40 thereafter be inclined to any desired angle without substantially affecting the uniformity of distribution of abrasive particles in the jets issuing from nozzles at the ends of the passages. The invention provides uniformity of abrasive or 45 blasting effect because, in a vertical riser, there is a random distribution of the particles in the air stream, that is, each unit volume of air, on the average, contains the same number of abrasive particles as every other unit volume.

50 In another form of the invention, it is not necessary that the supply conduit be a vertical riser. In accordance therewith, the abrasive particles in a supply conduit are separated by a vertical plane and delivered to two sub-divided pas- 55 sages. Even in a horizontal supply conduit, the

distribution of solid particles is symmetrical about a vertical diametrical plane. It is thus possible to obtain equal distribution of abrasive particles between two sub-divided passages if a vertical dividing plane is employed. The application of this principle may be carried to any desired extent, each of the first sub-divided passages being again divided by vertical walls to further sub-divide the stream into a plurality of branches. The number of branches ultimately employed 60 depends upon the number of nozzle jets desired for covering the area to be treated.

The second form of the invention may also be employed to advantage in connection with the first form between the symmetrical offtakes from 65 the vertical riser and the nozzle jets proper.

For a complete understanding of the invention, reference is made to the accompanying drawings illustrating a present preferred embodiment. In 70 the drawings:—

Figure 1 is a side elevation with parts in section of an apparatus for practicing the invention;

Figure 2 is an end view of the device shown in 75 Figure 1 taken substantially along the line II—II thereof;

Figure 3 is a sectional view along the plane of 80 line III—III of Figure 1;

Figure 4 is an elevation to enlarged scale of a 85 portion of the apparatus shown in Figure 1, with a part in section and parts removed;

Figure 5 is a section view along the plane of 90 line V—V of Figure 4;

Figure 6 is a sectional view along the plane of 95 line VI—VI of Figure 4;

Figure 7 is a plane view of a nozzle plate;

Figure 8 is a diagrammatic side elevation of 100 the invention in association with means for conveying a plate therebelow;

Figure 9 is a similar view showing a different 105 type of blasting apparatus;

Figure 10 is a partial plan view of the apparatus as shown in Figures 8 and 9;

Figure 11 is another view showing the apparatus for cleaning both sides of a metal plate simultaneously;

Figure 12 is a view similar to Figure 7 showing a modified form of nozzle plate; and

Figure 13 is a section view along the line XIII— 110 XIII of Figure 12.

Referring now in detail to the drawings and, for the present, particularly to Figures 1 through 7, the apparatus for practicing the invention comprises a vertical supply conduit 10 which is preferably provided with an inner tube 11 therein. A ring 12 spaces the tube 11 from the conduit 110

10. A distributor head 13 rests on the conduit 10 and is provided with a plurality of diverging passages 14. These passages are slightly tapering in cross section and are symmetrically disposed 5 with respect to the axis of the head and the conduit 10. A multiple passage elbow 15 is secured to the head 13 by bolts 16 and the head and elbow as a unit are connected to the conduit 10 by stud bolts 17 traversing a flange in the elbow 10 and a flange screwed on to the conduit 10. The elbow 15 includes a vertical portion 18 and inclined portions 19 and 20 integral therewith. Axial passages 21 are bored through the vertical portion of the elbow, the upper ends of which are 15 closed by plugs 22 forming clean-out ports. Inclined passages 23 are bored in the inclined portions 19 and 20 of the elbow and intersect the passages 21.

Multiple passage conduits 24 and 25 extend 20 upwardly from the inclined portions 19 and 20 of the elbow 15. The conduits 24 and 25 have a plurality of axial passages 26 therein registering with the passages in the elbow. The conduits 24 and 25 extend through a closure 27 in 25 the wall of a blasting machine. Brackets 28 and 29 extend from flanges on the conduits to the closure. A nozzle head 30 is carried at the upper ends of the conduits 24 and 25. Elbow portions 19 and 20, conduits 24 and 25 and the 30 nozzle head 30 are suitably flanged for connecting bolts, which are omitted for the sake of clearness of illustration.

The nozzle head 30 is shown in detail in Figures 4 through 7. The nozzle head comprises a 35 casting having tubular portions 31 and 32. These portions are bored to provide passages 33 registering with the passages 26 in the conduits 24 and 25. The passages 33 to the left of the central longitudinal plane passing through the head 40 30, as shown in Figure 5, are connected by passages 34 and 35 at right angles thereto, to nozzle ports 36. Similarly disposed passages 33 in the tubular portion 32 of the head have passages 37 and 38 connecting them to similar nozzle ports. Passages 39, 40, 41 and 42 likewise 45 connect the passages 33 on the other side of the vertical longitudinal plane to respective nozzle ports.

As stated, the nozzle head 30 is a casting and 50 the passages therethrough are preferably formed by tubes 43 cast integral therewith.

Nozzle plates 44 having aligned nozzles 45 are 55 removably secured to the nozzle head by yokes 46 and set screws 47. The yokes 46 embrace 55 securing lugs 48 on the nozzle head and attaching lugs 49 on the nozzle plates. Depressions 49a in the lugs 49 are adapted to receive the ends of the set screws 47.

As is obvious from Figure 6, the nozzles connecting with the several multiple passages are 60 spaced apart uniformly longitudinally of the nozzle head so that the head, including eight nozzles, is effective to direct abrasive blasts of uniform intensity against an extended area of a plate or other article positioned adjacent the nozzles.

Referring now to Figures 8 through 11 showing 65 methods of applying the apparatus above described to blasting methods, Figure 8 shows a set of three nozzle heads 50, 51 and 52 similar to the 70 head 30, disposed in side-by-side relation and offset laterally with respect to each other so that an area of considerable width is covered by the jets from the nozzles carried by the heads. Inclined shafts 53 and 54 carry supporting rolls 55 and 56 for conveying a sheet or plate 57 beneath

the jets from the nozzle heads for cleaning the 80 surface of the sheet. The latter is disposed in an inclined position so that the blasting material and the scale cleaned from the sheet will slide off the surface thereof and no brushing or wiping means will be necessary. The side-by-side and laterally offset relation of the nozzle heads may be more clearly observed in Figure 10. Figure 9 shows a set of nozzle heads 58, 59 and 60 arranged similarly to those of Figure 8 except that they are 85 in a horizontal instead of an inclined plane.

Figure 11 shows a similar arrangement in which 90 nozzle heads 61, 62 and 63 for cleaning the upper surface of a sheet are supplemented by nozzle heads 64, 65 and 66 disposed below the sheet for cleaning the bottom surface thereof. In Figures 9 and 11, conveying rolls 67 on shafts 68 are illustrated as typical conveying means for moving the sheet shown at 69 past the blasting nozzles. Guide rolls 70 may be employed also.

In the form of the invention heretofore described, a vertical supply conduit is essential because otherwise a random distribution of abrasive particles in the air stream is not obtained and it is only by symmetrically sub-dividing a supply 100 stream in which the particles have random distribution that it is possible to provide a plurality of small jets of uniform intensity. It is also possible to obtain this result by another means. Figure 12 shows a nozzle plate similar to that 105 shown at 44 in Figure 7. The nozzle plate of Figure 12, designated at 71, however, has a pair of discharge nozzles 72 for each inlet port 73. The individual stream supplied to the port 72, therefore, is divided into two smaller streams each 110 having an equal percentage of abrasive carried thereby. This type of nozzle plate presents certain advantages for use in connection with the nozzle head and distributor head already described, but also indicates that an air stream may 115 be divided into separate streams having the same amount of abrasive if the main stream is divided by a vertical plane. It is thus possible to avoid the necessity of having a vertical riser serve as a supply conduit. A horizontal supply conduit, 120 for example, could be provided with means for dividing an air stream passing therethrough along a vertical plane. Each of the resulting streams could be further sub-divided and the process carried to any desired extent to provide 125 a plurality of individual jets, each having the same amount of abrasive and therefore equally effective in cleaning a metal surface.

It will be apparent from the foregoing description that the applicant has provided a very simple 130 solution for the heretofore difficult problem of obtaining a uniform distribution of abrasive material in a plurality of branches leading from a main supply conduit.

Although I have illustrated and described herein but a single present preferred embodiment of the invention, together with a modification of a portion thereof, it is not limited to such forms of apparatus but may be otherwise embodied and practiced within the scope of the following claims 135 with all the advantages and benefits mentioned.

I claim:

1. In an apparatus for uniformly distributing 140 solid material carried by a fluid stream, the combination with a vertical supply conduit of substantial length whereby random distribution of said material occurs therein, of a plurality of individual passages branching symmetrically from said vertical conduit and extending to the point of delivery of said material.

2. Distributing apparatus for a mixture of fluid and solids comprising a supply conduit extending substantially vertically, a distributor head on said conduit at the upper end thereof, having a plurality of individual passages arranged symmetrically about the cross-section of the conduit, and a multiple passage elbow having passages registering with those of said head, connected to the head for conducting individual streams of fluid and solids to their points of application. 80
3. In an abrasive distributing apparatus, the combination with a supply conduit disposed substantially vertically, of a distributor head closing the upper end of said conduit, said head having a plurality of individual passages therethrough disposed symmetrically about the cross-section of said conduit, and an elbow having passages registering with those of said head for conducting abrasive to its point of application. 90
4. In an abrasive distributor, a supply conduit arranged substantially vertically, a distributor head on said conduit at the upper end thereof having a plurality of individual passages disposed symmetrically about the axis of said conduit, a multiple passage elbow on said head having passages registering with those of the latter, and a nozzle head having passages registering with those of said elbow and spaced longitudinally of the head to provide a plurality of abrasive jets effective over a substantial area. 100
5. In a method of handling solids carried in a fluid stream, the steps including conducting the stream substantially vertically upward and maintaining a uniform distribution of solids therein, sub-dividing it symmetrically about its axis while its upward flow is maintained into a plurality of smaller streams, and conducting said smaller streams to points of use. 105
6. In a method of uniformly distributing abrasive material carried by a fluid stream, the steps including conducting said stream substantially vertically and maintaining a uniform distribution of solids therein, sub-dividing it symmetrically about its axis, and conducting the sub-divisions of said stream to laterally aligned points of use. 115
7. In a method of blasting, the steps including directing a stream of fluid carrying a solid substance vertically, maintaining a uniform distribution of the solid in the stream, sub-dividing the upwardly moving stream symmetrically about its axis while its upward flow is maintained and conducting sub-divisions of the stream to points of use laterally aligned in a common plane. 120
8. A method of distributing solid material carried in an air stream including the steps of directing said stream upwardly to produce a random distribution of said material therein, and sub-dividing said stream while maintaining its upward direction of flow to produce a plurality of smaller streams having substantially the same portion of solid content. 125
9. In an apparatus for uniformly distributing material carried in a fluid stream, the combination with a substantially vertical supply conduit of substantial length to obtain random distribution of material therein, of a plurality of passages branching from said conduit and disposed symmetrically about the cross-section thereof, and nozzles communicating with said passages to form jets carrying substantially the same amount of material therein. 130
10. In an apparatus for uniformly distributing matter carried by a fluid stream, the combination with a vertical supply passage of substantial length whereby to obtain random distribution of the matter in said stream, of means for dividing said passage symmetrically of its cross-section into a plurality of separate passages. 135
11. A method of uniformly distributing solid matter suspended in a fluid stream comprising maintaining random distribution of the matter in a substantially vertical stream of fluid, dividing the stream symmetrically about its axis into a plurality of smaller streams and while maintaining the direction of travel of the streams substantially the same, and conveying said smaller streams to a point of use. 140
